PROCESS FOR PRODUCTION OF
RADIOACTIVE IRON

John A. Swartout, Oak Ridge, Tenn., assignor to
the United States of America as represented
by the United States Atomic Energy Commis-
sion

No Drawing. Application September 7, 1950,
Serial No. 183,657

8 Claims. (Cl. 204—154)

1

My invention relates to the production of radioactive iron, and particularly to an improved process for the production of radioactive iron of relatively high specific activity, which is adapted for use where only a low or moderate neutron flux is available.

Radioactive iron of high specific activity can be prepared by neutron bombardment of iron or an iron compound, for a sufficient time to approach saturation equilibrium, if a neutron flux of about 10^{13} neutrons per sq. cm. per second, or higher, is available. In view of the extremely small number of sources of neutron flux of this magnitude there has been a need for a suitable process for the production of radioactive iron of relatively high specific activity utilizing fluxes substantially below 10^{13} neutrons per sq. cm. per second.

When iron or an iron compound is bombarded at a low or moderate neutron flux, the specific activity at saturation equilibrium is undesirably low, and attempts have therefore been made to secure a concentration or enrichment of the radioactive product. Such attempts have generally utilized the "Szilard-Chalmers" effect, in accordance with which a portion of the bombarded material is found to differ in chemical composition from the original material, and this portion, together with its associated radioactive product, may then be separated by chemical means, thus resulting in a concentration or enrichment. The Szilard-Chalmers reactions thus far employed, however, have generally not produced products of as high specific activity as desired, and have required adsorption, extraction, carrier precipitation, or other complex separation procedures.

An object of my present invention, therefore, is to provide an improved process for the production of radioactive iron of relatively high specific activity which requires the use of only a low or moderate neutron flux.

Another object of my invention is to provide such a process which employs an extremely simple separation procedure for effecting the desired concentration or enrichment.

A further object of my invention is to provide such a process which is readily adaptable to continuous operation.

Additional objects and advantages of my invention will be evident from the following description.

In accordance with my present invention magnesium ferrocyanide is subjected to neutron bombardment and the water-insoluble fraction of the bombarded material, together with its asso-

2

ciated radioactive iron, is separated from the water-soluble fraction. The separation procedure of my process thus involves only the very simple expedient of separating a precipitate from an aqueous solution. Utilizing controlled bombardment conditions, as hereinafter described, this process is capable of concentrating the bulk of the radioactive iron in a very small insoluble fraction of the bombarded material, thus effecting a high degree of concentration or enrichment.

The magnesium ferrocyanide to be bombarded in accordance with the present invention may be in any convenient form, but is preferably pure crystalline $Mg_2Fe(CN)_6 \cdot 12H_2O$. Aqueous solutions may also be employed, as will later be discussed, but my invention will be particularly described and illustrated with reference to the use of the crystalline salt. For most purposes the magnesium ferrocyanide may contain iron of natural isotopic distribution, which will result in a product containing Fe^{59} and Fe^{55} in a ratio of about 1.25 millicurie of Fe^{59} per millicurie of Fe^{55} . The Fe^{59} in such a product is of most interest in view of its half-life of 46 days and its relatively much harder radiation. The four year half-life Fe^{55} in a neutron bombarded compound of natural iron can be neglected in most chemical tracer uses, but is undesirable for many biological uses. If the product is to be employed for biological purposes, therefore, it is desirable to prepare the magnesium ferrocyanide from iron enriched in Fe^{58} , or from the pure isotope Fe^{58} . For special purposes other enrichments or other pure isotopic compounds can, of course, also be employed.

It is desirable to remove any water-insoluble constituents from the magnesium ferrocyanide prior to bombardment, especially if a commercially available salt is to be used. For this purpose it is sufficient to dissolve the salt in water, to about 0.1 M concentration, remove any insoluble matter by centrifugation or other suitable means, concentrate the remaining solution, and recrystallize the salt.

The magnesium ferrocyanide, purified as described above, or by any equivalent procedure, is then placed in a suitable container for neutron bombardment. Thin-walled quartz vessels are desirable for this purpose, and such vessels can suitably be protected from mechanical shock and the like by means of outer containers of aluminum, zirconium, or other material of low neutron absorption cross-section.

Any of the known types of neutron sources may be employed for bombarding the magnesium ferrocyanide in accordance with my invention.

The neutron flux available from targets bombarded by accelerated charged particles, or from radioactive sources such as radium-beryllium and polonium-beryllium sources, is generally so low as to result in an undesirably low rate of production of radioactive iron. For practical production rates the neutron flux should be at least 10^9 n/sq. cm./sec. Although cyclotron bombardment of certain target materials can yield neutron fluxes above 10^9 n/sq. cm./sec. the preferred neutron sources are uranium or plutonium nuclear reactors, particularly reactors providing a thermal neutron flux of about 10^{11} n/sq. cm./sec. to 10^{12} n/sq. cm./sec. If the nuclear reactor operates at a neutron energy substantially above the thermal range, or if another type of neutron source is employed which provides high energy neutrons, it is preferred to interpose a moderator such as carbon, beryllium, or a hydrogenous material, between the source and the magnesium ferrocyanide being bombarded.

It should be understood that my process is completely operative when employing a neutron flux of 10^{13} n/sq. cm./sec. or higher; its advantages over other available processes are merely less pronounced at a very high neutron flux.

The preferred time of bombardment of the magnesium ferrocyanide will depend on the neutron flux employed, but can be expressed in terms of the saturation time, i. e. the time beyond which further production of radioactive product is offset by radioactive decay, resulting in an equilibrium concentration or specific activity. The bombardment time should be less than 0.5 and preferably less than 0.1 of the saturation time. With neutron fluxes in the range 10^{11} – 10^{12} n/sq. cm./sec., bombardment times of 1–50 days may suitably be employed, with a time of less than 15 days being preferred.

At neutron fluxes below about 10^{13} n/sq. cm./sec. the specific activity of the product obtained by the present process decreases with increasing time of bombardment even though the total quantity of active product increases with increasing time of bombardment. If maximum specific activity is desired, therefore, the time of bombardment should be only long enough to produce the minimum separable insoluble fraction in the bombardment product. This minimum, about 10^{-5} gram of iron in the insoluble fraction per gram of $Mg_2Fe(CN)_6 \cdot 12H_2O$ bombarded, is attainable with a bombardment time of about 12 hrs. at a neutron flux of about 10^{12} n/sq. cm./sec. Somewhat longer bombardments, giving an insoluble fraction containing about 10^{-4} gram of iron per gram of $Mg_2Fe(CN)_6 \cdot 12H_2O$ bombarded, are generally desirable to facilitate the separation of the insoluble material.

The magnesium ferrocyanide may be bombarded at any temperature below its thermal decomposition temperature, i. e., about 200° C. However, even minute amounts of thermal decomposition products tend to dilute the insoluble fraction of the bombarded material and thus reduce its specific activity. It is generally desirable, therefore, to effect the bombardment at a temperature below 150° C., and it is preferred, especially for bombardments of relatively short duration, to maintain the magnesium ferrocyanide within the range 20 – 90° C. during bombardment.

At the conclusion of the bombardment the container of bombarded material is removed from the neutron flux and preferably stored in a

shielded area for 2 hrs. or longer to permit radioactive decay of the Mg^{27} (10 min. half-life) and of any short-lived activities induced in the container materials. The container is then opened and the bombarded material is introduced into a quantity of water sufficient to produce a solution 0.05–0.25 M, and preferably about 0.1 M with respect to $Mg_2Fe(CN)_6 \cdot 12H_2O$.

The resulting insoluble precipitate is then separated from the supernatant solution by any suitable procedure such as sedimentation or filtration, but preferably by centrifugation. This precipitate, which will generally contain about 8% of the total radioactivity of the bombarded material, may be merely dried for use as such, or may be ignited or subjected to other treatment to produce a product of the desired chemical constitution for its proposed radioactive application. The magnesium ferrocyanide in the separated supernatant solution may, of course, be recrystallized for further bombardment.

It will be evident that the process previously described is readily adaptable to continuous operation by the expedient of bombarding the magnesium ferrocyanide in the solution from which the insoluble bombardment product is to be separated. For this purpose H_2O or D_2O solutions of magnesium ferrocyanide may be continuously circulated through a nuclear reactor, the insoluble bombardment product may be continuously separated by centrifugation, and the supernatant solution continuously recycled to the reactor.

Neutron fluxes, temperatures, bombardment times, and concentrations which are suitable for the crystal bombardment process may also be employed for the continuous solution bombardment process. Temperatures substantially below 100° C. are preferred, however, in order to avoid the use of superatmospheric pressure. The residence time in the nuclear reactor, per cycle, should also preferably be somewhat shorter than the corresponding bombardment time for the crystalline material, with a circulation rate sufficiently high to prevent deposition of the insoluble bombardment product in parts of the apparatus other than the centrifuge.

My invention will now be further illustrated by means of specific examples involving the bombardment of crystalline $Mg_2Fe(CN)_6 \cdot 12H_2O$ of natural isotopic content:

Example I

Recrystallized $Mg_2Fe(CN)_6 \cdot 12H_2O$ was placed in a fused quart vessel within an aluminum outer container, which was positioned in a water-jacketed tube within a nuclear reactor. The water flowing through the jacket of the tube was maintained at 25° C., and the flux level in the vicinity of the tube was about 10^{12} n/sq. cm./sec. Bombardment was continued for 46 days (one half-life period of Fe^{59}) after which the container was removed from the reactor and stored to permit decay of short-lived activities.

The container was then opened, a portion of the bombarded material was introduced into a sufficient quantity of water to form a solution 0.1 M with respect to $Mg_2Fe(CN)_6 \cdot 12H_2O$, and the resulting precipitate was separated by centrifugation. The iron content of the precipitate was determined by the orthophenanthroline-ferrous complex colorimetric method, after dissolving in HCl .

The Fe^{59} activities of aliquots of the precipitate, the supernatant solution, and the unseparated irradiated salt were then determined by

means of conventional counting methods, employing a high-pressure argon-filled ionization chamber. It was found that approximately 80% of the total Fe^{59} activity of the bombarded material was concentrated in the precipitate, and that the specific activity of the precipitate was approximately 24 millicuries of Fe^{59} per gram of iron content.

The following example illustrates the effect of bombardment time on yield of total product and on specific activity of the product produced:

Example II

Portions of $\text{Mg}_2\text{Fe}(\text{CN})_6 \cdot 12\text{H}_2\text{O}$ were bombarded as in Example I, for various times as shown in the table below. The bombarded materials were then treated and analyzed as in Example I, with the additional determination of the iron content of the precipitate per gram of original $\text{Mg}_2\text{Fe}(\text{CN})_6 \cdot 12\text{H}_2\text{O}$. This value, together with the specific activity of the bombarded salt, and of the precipitate, are shown in the table below:

Bombard- ment Time (days)	Wt. of Fe in Precipitate Per g. of Original Salt	Specific Activity (milli- curies per gram)	
		Bombarded Salt	Precipitate
3.75	1.22×10^{-4}	0.05	35.6
5.2	1.63×10^{-4}	0.06	34.7
6.6	2.23×10^{-4}	0.08	32.8
12.3	4.78×10^{-4}	0.15	31.1
79.0	27.5×10^{-4}	0.63	23.2

It will be noted from the above table that the quantity of precipitate increased roughly linearly with time, whereas the specific activity of the precipitate decreased roughly linearly with respect to the logarithm of the time.

It should be understood, of course, that the above examples are merely illustrative, and that the scope of my invention should be limited only as indicated by the appended claims.

I claim:

1. A process for the production of radioactive iron which comprises subjecting magnesium ferrocyanide to neutron bombardment and separating the resulting water-insoluble fraction from the bombarded material.

2. A process for the production of radioactive iron which comprises subjecting crystalline $\text{Mg}_2\text{Fe}(\text{CN})_6 \cdot 12\text{H}_2\text{O}$ to neutron bombardment at a flux of 10^9 - 10^{12} n./sq. cm./sec. for a time sufficient to form a separable water-insoluble fraction of the bombarded material but less than 0.5 of the saturation time, introducing the bombarded material into water to dissolve the unchanged magnesium ferrocyanide, and separating the resulting precipitate from the supernatant solution.

3. A process for the production of radioactive iron which comprises subjecting crystalline $\text{Mg}_2\text{Fe}(\text{CN})_6 \cdot 12\text{H}_2\text{O}$ to neutron bombardment at a flux of 10^9 - 10^{12} n./sq. cm./sec. for a time sufficient to form a separable water-insoluble fraction of the bombarded material but less than 0.1 of the saturation time, while maintaining the temperature of said $\text{Mg}_2\text{Fe}(\text{CN})_6 \cdot 12\text{H}_2\text{O}$ below 150° C., introducing the bombarded material into water to form a 0.05-0.25 M solution of the unchanged magnesium ferrocyanide, and separat-

ing the resulting precipitate from the supernatant solution.

4. A process for the production of radioactive iron which comprises subjecting crystalline $\text{Mg}_2\text{Fe}(\text{CN})_6 \cdot 12\text{H}_2\text{O}$ to neutron bombardment at a flux of 10^{11} - 10^{12} n./sq. cm./sec. for a time sufficient to form a separable water-insoluble fraction of the bombarded material but less than 0.1 of the saturation time, while maintaining the temperature of said $\text{Mg}_2\text{Fe}(\text{CN})_6 \cdot 12\text{H}_2\text{O}$ within the range 20-90° C., introducing the bombarded material into water to form an approximately 0.1 M solution of the unchanged magnesium ferrocyanide, and separating the resulting precipitate from the supernatant solution.

5. A process for the production of radioactive iron which comprises subjecting crystalline $\text{Mg}_2\text{Fe}(\text{CN})_6 \cdot 12\text{H}_2\text{O}$ to neutron bombardment at a flux of approximately 10^{12} n./sq. cm./sec. for 0.5 to 15 days while maintaining the temperature of said $\text{Mg}_2\text{Fe}(\text{CN})_6 \cdot 12\text{H}_2\text{O}$ within the range of 20-90° C., introducing the bombarded material into water to form an approximately 0.1 M solution of the unchanged magnesium ferrocyanide, and separating the resulting precipitate from the supernatant solution.

6. A process for the production of radioactive iron which comprises continuously circulating an aqueous solution of magnesium ferrocyanide through a zone of neutron flux, continuously withdrawing said solution from said zone of neutron flux, continuously separating insoluble material from said withdrawn solution, and continuously recycling the resulting supernatant solution to said zone of neutron flux.

7. A process for the production of radioactive iron which comprises continuously circulating a 0.05-0.25 M solution of magnesium ferrocyanide through a zone of neutral flux of 10^9 - 10^{12} n./sq. cm./sec. while maintaining the temperature of said solution within the range 20-90° C., continuously withdrawing said solution from said zone of neutron flux, continuously separating insoluble material from said withdrawn solution, and continuously recycling the resulting supernatant solution to said zone of neutron flux.

8. A process for the production of radioactive iron which comprises continuously circulating an approximately 0.1 M solution of magnesium ferrocyanide through a nuclear reactor having a neutron flux of about 10^{12} n./sq. cm./sec. while maintaining the temperature of said solution within the range 20-90° C., continuously withdrawing said solution from said nuclear reactor, continuously separating insoluble material from said withdrawn solution, and continuously recycling the resulting supernatant solution to said nuclear reactor, the average residence time of the solution in said nuclear reactor, per cycle, being of the order of 1 day.
